W. THOMA

CLUTCH

Filed Feb. 14, 1924

Fig. 1.

Fig. 2.

INVENTOR :

Walter Thoma,

By Attorneys,
Fraser Myers & Menley

UNITED STATES PATENT OFFICE.

WALTER THOMA, OF BROOKLYN, NEW YORK, ASSIGNOR TO E. W. BLISS COMPANY, OF BROOKLYN, NEW YORK, A CORPORATION OF WEST VIRGINIA.

CLUTCH.

Application filed February 14, 1924. Serial No. 692,675.

To all whom it may concern:

Be it known that I, WALTER THOMA, a citizen of the United States of America, residing at Brooklyn, in the county of 5 Kings and State of New York, have invented certain new and useful Improvements in Clutches, of which the following is a specification.

This invention relates to clutches, and 10 more particularly to the clutch-operating mechanism by which the clutch-pin or key is moved into and out of clutching position, and aims to provide improvements therein.

15 In the type of clutch employing a key or pin which is turned to effect clutching and declutching of the driving and driven parts, the part which makes contact with said key or pin for turning the latter, is 20 subjected to shocks of considerable amount and number, and to minimize wear and injury to said part it is customary to provide a spring to cushion the shock. The reaction of the spring on the part in question, however, produces a secondary impact of said part, and this in turn produces fatigue of the metal, which in time causes breakage. Breakage of a part of the clutch-operating mechanism is of course objectionable in 25 itself, and is apt to cause injury to the machine to which it is applied and to the operator.

30 The present invention provides a means whereby the secondary impact of the said part which engages the clutch-key is avoided, and breakage due to fatigue thus avoided.

An embodiment of said invention is illustrated in the accompanying drawings, in 35 which,—

40 Figure 1 is a side elevation (partly in section) of said embodiment applied to a press (only so much of the press being illustrated as is necessary to convey an understanding of the invention).

45 Fig. 2 is a similar view, the parts being shown in position of reaction to the primary impact on the clutch-operating mechanism.

50 The clutch to which this invention is shown as applied, is an invention of Robert W. Strout, and is fully illustrated and described in his United States Patent No. 1,481,444, dated January 22, 1924. The in-

vention may be applied generally to 55 clutches of this type.

This clutch comprises an oscillating key or pin A carried by a crank-shaft B, and adapted to be connected to and disconnected from a flywheel (not shown) turning on 60 said crank-shaft, by the turning of said key or pin A. The turning of the key A in one direction (to declutching position) is effected through an arm or tail-piece C, while turning thereof in the opposite direction (to clutch) is effected by a spring (not shown). The particular tail-piece C shown has a shoulder D, and a portion E beyond the shoulder D which is concentric with the axis F of rotation of the crank-shaft B 70 in the declutched position of the key A (shown in Figs. 1 and 2).

The clutch-operating means comprises a part 10 adapted to be moved into and out of the path of the tail-piece C of the key 75 A, and to this end the part 10 is conveniently fixed on a rock-shaft 12, which is adapted to be turned by suitable means such as a treadle (not shown) connected through a rod 14 and an arm 16 to said rock-shaft 80 12. The arm 16 is ordinarily held in place on said shaft 12 by a threaded nut 17. The shaft 12 is journaled in suitable bearings 18, 19, on the side frame of the press and is preferably arranged with its axis substantially parallel to a tangent at the point 85 of impact of the part 10 and tail-piece C.

When the part 10 of the clutch-operating mechanism is moved into the path of revolution of the tail-piece C, the said part 10 90 will be struck by said tail-piece (shoulder D in the construction shown). The rock-shaft 12 is made axially movable in its bearings, and the reactions from the impact will turn the key A and tail-piece C to the 95 position shown in Fig. 1 and will move the rock shaft 12 axially to substantially the position shown in Fig. 2.

A spring 22 for cushioning the impact on the part 10 is provided. This spring is 100 preferably a coil spring surrounding the rock-shaft and bearing on a shoulder 24 thereon and on a sleeve 26 threaded in the bearing 19. A washer 28 is preferably arranged on the rock-shaft 12 in such manner 105 that the spring bears on the shoulder 24 through the washer.

When the rock shaft 12 has reacted under

the impact of the tail-piece C and part 10 on said shaft, the spring 22 is tensioned, and after the momentum of the crank-shaft B has carried the key A and tail-piece C somewhat further around in the direction of rotation, so that the concentric portion E overlies the part 10, the reaction of the spring 22 shoots or impels the rock-shaft 12 axially in the direction opposite to that in which it reacted under the impact of the parts 10 and C. If the reaction of the spring 22 be sustained by the arm 16 or nut 17 striking the bearing 19, fatigue will be set up in the metal of the shaft 12 and in time the shaft 12 will break adjacent the arm or nut. This is, of course, objectionable and apt to result in further disorder dangerous to both the press and the press operator.

According to the present invention the parts are arranged to avoid shock on the shaft 12 on reaction of the spring 22. This is effected by arranging the spring 22 so that it will make contact with the bearing 18 (or other stop) before the arm 16 strikes the end of bearing 19 (or other stop), so that the tension of the spring 22 is taken off of the shaft 12 before the arm 16 strikes. The momentum of the shaft 12, after being relieved of the push of the spring 22, is quickly overcome by the resistance or friction of the part 10 against the tail-piece C, so that by a slight movement beyond the position where the spring comes into contact with bearing 18 (see Fig. 1) the shaft 12 may be stopped, and even stopped without any impact of the arm 16 against bearing 19. The spring 22 is here shown as bearing against the washer 28, and the washer makes contact with the bearing 18, allowing shoulder 24 on the shaft 12 to move away from the washer. By the present invention breaking of the clutch-operating mechanism due to shock arising either directly or indirectly from the contact between said mechanism and the clutch-key is practically avoided.

The invention may receive other embodiments than that herein specifically illustrated and described.

What I claim is:

1. Clutch-operating mechanism comprising a part adapted to make contact with a part of a clutch-key or pin, a spring for cushioning the shock of contact between said operating part and clutch part, and means for relieving said operating part of shock on the reaction of said spring. 55

2. Clutch-operating mechanism comprising a rock-shaft having a part thereon adapted to be turned to make contact with a part of a clutch-key or pin, a spring for cushioning the shock of contact between said part on said rock-shaft and said clutch part, and means for relieving said rock-shaft of shock on the reaction of said spring. 65

3. Clutch-operating mechanism comprising a rock-shaft having a part thereon adapted to be turned to make contact with a part of a clutch-key or pin, and having axial movement, a spring adapted to bear 70 on said rock-shaft to oppose axial movement thereof and thereby to cushion the shock of contact between said part on said rock-shaft and said clutch part, and means for relieving said rock-shaft of the action 75 of said spring on reaction, said rock-shaft being axially movable beyond the point where it is relieved of the action of said spring.

4. Clutch-operating mechanism comprising a rock-shaft having a part thereon adapted to be turned to make contact with a part of a clutch-key or pin, and having axial movement, a shoulder on said rock-shaft, a washer loose on said shaft and abutting said shoulder, a spring adapted to bear through said washer on said rock-shaft to oppose axial movement thereof and thereby to cushion the shock of contact between said part on said rock-shaft and said clutch part, 85 and a stop for engaging said washer on the reaction of said spring, said rock-shaft being axially movable beyond the point where said washer makes contact with said stop, whereby said shoulder may move away from 90 said washer and said rock-shaft be relieved of the action of said spring. 95

In witness whereof, I have hereunto signed my name.

WALTER THOMA.
